No. 818,785.

PATENTED APR. 24, 1906

F. A. PLATZ.

GARMENT.

APPLICATION FILED MAR. 16, 1904.

UNITED STATES PATENT OFFICE.

FRANK A. PLATZ, OF BROOKLYN, NEW YORK.

GARMENT.

No. 818,785.

Specification of Letters Patent.

Patented April 24, 1906.

Application filed March 16, 1904. Serial No. 198,381.

To all whom it may concern:

Be it known that I, FRANK A. PLATZ, a citizen of the United States, residing at Brooklyn, in the county of Kings and State of New York, have invented certain new and useful Improvements in Garments, of which the following is a specification, such as will enable those skilled in the art to which it appertains to make and use the same.

This invention relates to children's garments, and particularly to underwaists or undervests; and the object thereof is to provide a garment of this class which is strong and durable and which is provided with improved fastening devices and improved means for suspending the lower garments therefrom, such means and devices being detachable from the garment, so as to prevent injury thereto when the garment is laundered, a further object being to provide improvements of this class which may be applied to shirts or shirt-waists and blouses; and with these and other objects in view the invention consists of the construction, combination, and arrangement of parts hereinafter described and claimed.

This invention is an improvement on that described and claimed in United States Letters Patent No. 690,768, granted to me January 7, 1902, and is fully disclosed in the following specification, of which the accompanying drawings form a part, in which the separate parts of my improvement are designated by suitable reference characters in each of the views, and in which—

Figure 1 is a front view of an under vest or waist for children provided with my improvement; Fig. 2, a back view thereof; Fig. 3, an inside view showing the garment extended and the shoulder-strap portions broken; Fig. 4, a section on the line 4 4 of Fig. 3; Fig. 5, a section on the line 5 5 of Fig. 3; Fig. 6, a view similar to Fig. 5, but showing a modification, a part of the garment shown in Fig. 5 being omitted; Fig. 7, a view similar to Fig. 3, showing a part of a shirt-waist or similar garment with my improvement or a part thereof applied thereto; Fig. 8, a section on the line 8 8 of Fig. 7; Fig. 9, a front view showing a modification of the construction shown in Fig. 5, and Fig. 10 a side view thereof.

In the practice of my invention, as shown in Figs. 1 to 4, inclusive, I provide a child's under waist or vest composed of a back *a* and side members *a*², connected at *a*³ in the usual

manner and provided with armholes *a*⁴, and in Fig. 3 of the drawings the shoulder-strap portions of this garment are broken or separated, as shown at *a*⁵. The side portions *a*² 60 are adapted to be connected at the front by means of buttons *a*⁶ or in the usual or any preferred manner, and in the form of construction shown the bottom portion of the under waist or vest is composed of a separate 65 piece *a*⁷, secured to the back and sides at *a*⁸ by stitching or sewing or in any desired manner; but the bottom part *a*⁷ may be formed integrally with the back and sides, if desired.

Extending entirely around the bottom 70 portion of the garment and at the point *a*⁸, where the bottom portion *a*⁷ is secured, and on the outside of the garment is a strap or band *b*, which is permanently attached to said garment by stitching or otherwise, and 75 said strap or band is composed of tape or any suitable flexible fabric, and in the form of construction shown the opposite side portions of the garment are provided with reinforcing-strips *b*², which extend from the strap 80 or band *b* at the front of the garment up over the shoulders and down to the strap or band *b* at the back of the garment. The seams at *a*³, where the back *a* and side portions *a*² of the garment are connected, are also covered 85 by reinforcing-strips *b*³, which extend from the armholes *a*⁴ downwardly and backwardly to the band *b*, and similar reinforcing-strips *b*⁴ are arranged between the front portions of the strips *b*² and the strips *b*³ and extend from 90 the armholes *a* downwardly to the band *b*, and the strips *b*², *b*³, and *b*⁴ are preferably composed of binding-tape or other similar fabric.

The back part *a* of the garment is provided 95 at the inner side thereof with a reinforcing-piece *c*, which covers the entire upper inner part of said back part *a* and extends to the neck-opening *a*⁹, to the armholes *a*⁴, and downwardly, as shown at *c*², to a point mid-100 way between the armholes and the strap or band *b*, and the bottom portion of which is folded upwardly, as shown at *c*³, and stitched to the back part *a* of the garment transversely thereof and also to the body portion 105 of the reinforcing-piece *c*, as shown at *c*³, and the neck-opening *a*⁹, the armholes *a*⁴, and all the outer edges of the garment, including the front edges of the side portions *a*² and the bottom portion of the garment, are preferably 110 provided with a binding *c*⁴.

The buttons *a*⁶, which connect the side por-

tions of the garment at the front thereof, are secured to a vertically-arranged flexible and detachable strip d at the inner side of one of the side portions a^2 of the garment, and secured to the bottom portion of said strip is a similar flexible and detachable strip d^2 , also on the inner side of the garment and extending approximately around the same, and the strip d^2 is also provided at d^3 with buttons which are arranged to correspond with the position of the lower ends of the strips b^2 and b^4 at the front of the garment and which are adapted to be passed through buttonholes d^4 at these points and as shown in Fig. 5, and in the form of construction shown the strip d^2 , which is on the inner side of the garment, is directly over the strap or band b , which is on the outer side of the garment, and the buttons d^3 serve to hold the strip d^2 in proper position, and it will be understood that the strips d and d^2 may be detached from the garment whenever desired.

Secured to the strip d^2 at the point where the buttons d^3 are passed through buttonholes d^4 at the front lower ends of the reinforcing-strips b^4 are flexible suspending-straps e , which are passed out through slots or openings e^2 , formed in the side portions a^2 of the garment, and these suspending-straps are formed into loops e^3 , with which are connected buckles or similar devices e^4 , with which are connected straps e^5 , which serve as supports for the stockings, and the loops e^3 of the straps e are provided with supplemental depending members e^6 , having buttons e^7 , whereby the bottom of the underwaist or vest may be connected with the waistband of the lower garments. Neither the buckle e^4 nor the strap e^5 is shown in Fig. 5; but these parts are shown at the left-hand side of Fig. 1, and the button e^7 and supplemental member or strap e^6 , with which it is connected, are shown at the right-hand side of Fig. 1.

The buttons e^7 at the front of the bottom portion of the garment are intended for connection with the lower garments at the front, and I also provide other supports for the lower garments at the back, and these supports consist of flexible straps f , three of which are shown, and these straps are buttoned to the part of the fold c^2 at the bottom of the reinforcing member c of the back a of the garment, this connection being indicated in dotted lines at f^2 in Fig. 3 and shown in section in Fig. 4, and the straps f are passed outwardly through slits or slots f^3 in the bottom portion of the back of the garment and are provided with buttons f^4 for connection with the waistband at the back of the lower garments, and the middle strap f is longer than the other straps f , as shown in Fig. 2, and is provided at its lower end with a supplemental button f^5 , which is designed to form a connection and support for the lower undergarments. As thus constructed it will

be seen that the straps f are detachable from the garment in the same manner as the straps d and d^2 , and all these parts may be detached when it is desired to launder the garment and replaced in position when it is desired to use the garment.

In Fig. 6 I have shown a modification of the suspending strap or device e shown in Fig. 5, and in this modification both ends of said strap are connected with the strip d^2 , and said strip is formed into two loops e^8 and e^9 , and the button e^7 is connected with the lower loop e^9 , while the supplemental suspending-strap e^5 , which is designed to form a stocking-support, is connected with the loop e^8 by means of a buckle, safety-pin, or similar device g .

In Figs. 9 and 10 I have shown another modification of the strap attachment or suspending device shown in Figs. 4 and 6, and in this form of construction the strap e is formed into a single loop h , the front upper part of which is provided with eyelets h^2 , by means of which a safety-pin or other fastening device h^3 , to which the supplemental suspending-strap e^5 is secured, is connected therewith, and the button e^7 is secured to the lower part of the loop h , as clearly shown in said figures.

In Figs. 7 and 8 I have shown a modification in which my improvement or a part thereof is applied to the back i of a shirt-waist or similar garment, and in this construction I secure to the inner side of the back of the shirt-waist a reinforcing-piece i^2 , which extends from the neck-opening i^3 downwardly to a point just above the waist-line, as shown at i^4 , and the lower end of the reinforcing-strip i^2 is folded inwardly and upwardly and stitched to the back i of the shirt-waist and to the body portion of said reinforcing-strip, as shown at i^5 . In this form of construction flexible straps j , similar to the straps f in Fig. 4, are buttoned to the bottom fold at i^4 of the reinforcing-piece i^2 , as shown at j^2 , and these straps j are passed through a reinforcing-strip j^3 , secured to the back of the shirt-waist and outwardly through said back, as shown at j^4 , and each of said straps is provided with a button j^5 , and the middle strap j is longer than the straps at the opposite sides thereof and is provided with a supplemental button j^6 , and the straps j are intended for the same purpose as the straps f . (Shown in Figs. 3 and 4.)

The reinforce-piece c , secured to the back a of the garment shown in Figs. 1 to 4, inclusive, is also provided with a flexible loop k , which is secured thereto centrally of the bottom fold thereof and through which the detachable strap d^2 is passed, so as to support said strap centrally of the back.

It will be apparent that my improvements may be applied to any kind or class of a washable vest, jacket, or shirt-waist, and by means of my improvement I am enabled to

detach all the suspending and fastening devices, including those which hold the garment together at the front, and whenever it is desired to wash the garment all of said devices 5 are removed therefrom, and this can be quickly, conveniently, and easily done, and said devices may be reattached to the garment whenever desired in the same manner.

Having fully described my invention, what 10 I claim as new, and desire to secure by Letters Patent, is—

1. In a garment of the class described, the combination with the body thereof having a band encircling the same at the waist, said 15 garment having openings at the front thereof, and said band having slits below the openings of the body, of a band arranged at the inner side of the body and provided with fastening devices which engage said openings of 20 the body for detachably connecting the band therewith, and suspending devices connected to said inner band and projected through the slits of the outer band.

2. In a garment of the class described, the 25 combination with the body thereof, of a rein-

forced member arranged at the back of said body and extending from the upper portion thereof to the waist, said reinforced member having a fold formed at its lower end separated from the back of the garment, the latter 30 having a series of slits in the back at a point below the fold of the reinforced member, and suspending devices projected through said slits, the upper ends of said suspending devices having fasteners connected to said fold 35 and positioned between the same and the back of the body, whereby said fasteners are free from contact with the undergarments of the wearer, and the lower end of said suspending devices having fastening devices 40 connected thereto.

In testimony that I claim the foregoing as my invention I have signed my name, in presence of the subscribing witnesses, this 12th day of March, 1904.

FRANK A. PLATZ.
